UNITED STATES PATENT OFFICE.

HERMAN HOUSE, OF VANCOUVER, BRITISH COLUMBIA, CANADA.

PHONOGRAPH REPEATER.

Application filed January 5, 1926. Serial No. 79,401.

My invention relates to and has for its purpose the provision of an extremely simple and inexpensive device readily attachable to any phonograph of conventional form for 5 actuating the stylus to repeat the playing of the record indefinitely and automatically by utilizing the movement of the phonograph turntable and to the exclusion of extraneous or supplemental springs or other 10 actuating devices.

It is also a purpose of my invention to provide a phonograph repeater which in effecting the repeated playing of a record automatically actuates the stylus with such 15 ease of operation as to completely eliminate noise and injury to the record.

I will describe only one form of phonograph repeater embodying my invention and will then point out the novel features there- 20 of in claims.

In the accompanying drawings,

Figure 1 is a view showing in top plan one form of repeater embodying my invention in applied position to a conventional form of 25 phonograph;

Figure 2 is a view showing the repeater in side elevation and in applied position to a phonograph;

Figures 3 and 4 are fragmentary views 30 showing in side elevation two positions which the cam member occupies during operation thereof;

Figure 5 is a fragmentary vertical sectional view showing the mounting for the 35 disk supporting arm of the repeater;

Figure 6 is a vertical sectional view taken on the line 6—6 of Figure 5;

Figure 7 is a fragmentary sectional view taken on the line 7—7 of Figure 2.

Similar reference characters refer to simi- 40 lar parts in each of the several views.

Referring specifically to the drawings, my invention, in its present embodiment, is shown applied to a conventional form of 45 phonograph comprising a platform 15 through which extends a shaft 16 carrying a turntable 17 and upon which a record 18 is adapted to repose and be rotated in the usual manner. A pivoted tone arm 19 is 50 provided with a sound box 20 carrying a stylus 21 which is adapted to engage within the sound groove of the record and on the rotational movement of the latter to be fed inwardly toward the center of the disk.

The repeating device embodying my invention 55 comprises a bracket 22 secured to and upstanding from the platform 15 and slotted to receive a U-shaped head 23 of an arm 24, the head being fulcrumed on a pin 25 extending through the bracket. Through 60 the medium of this pin 25, the arm, together with the head, is pivotally supported to occupy substantially horizontal position, as shown in Figure 2, or an elevated position, in which latter position the arm is latched 65 by a pin 26 engaging within a suitable recess in the head 23 and urged to this position by a spring 27, all as clearly shown in Figure 6. The arm 24 is limited in its downward movement to the aforementioned horizontal position by a pin 28 extending through the bracket and engaging one of the parallel 70 portions of the head 23. A screw 29 adjustable in the bracket 22 engages the other parallel portion of the head and by adjustment may vary the position of the arm 24 for a purpose which will be hereinafter described.

As clearly shown in Figure 1, the arm 24 is curved in an arc concentric with respect 80 to the pivot of the tone arm 19, and at the outer end of this arm a disk 30 is rotatably mounted thereon, such disk being provided with a flat peripheral portion 31. Fixed to the disk is a cam member 32 carrying a 85 projection 33 adapted to be engaged by a tripping member 34 adjustable on an arm 35 and adapted to be locked and a finer adjustment secured through the medium of a screw 36. This arm 35 is likewise curved 90 on an arc concentric with respect to the pivot of the tone arm and, as shown in Figure 1, it is pivotally connected at the point indicated at 37 to a bracket 38 so as to swing in a horizontal plane. The bracket in turn is 95 secured to the tone arm adjacent the sound box 20, and a stop arm 39 is fixed to the bracket 38 for engagement with a stop finger 40 constructed as shown for adjustment longitudinally on the arm 24. To provide a 100 finer adjustment for the stop finger 40 with respect to the stop arm a screw 41 is adjustably mounted in the stop finger 40. Although slidable on the arm 24, the finger 40 automatically locks itself against movement rearwardly on the arm by a reversely bent extension 40^a engaging the lower edge 105 of the arm to frictionally resist rearward

- movement so that when engaged by the stop arm 39 it positively checks the arm 35 in its rearward movement. The tripping member 34 carries a resilient extension 34^a which is 5 positioned to have frictional engagement with the arm 35 to resist movement of the member 34 rearwardly on the arm 35 so that after it has been once adjusted it maintains its adjustment.
- 10 As shown in Figures 2 and 7, the disk end of the arm 24 carries a handle 42 which is adapted to be gripped in manipulating the arm 24, and likewise secured to the arm is a latch member 43 adapted to engage within 15 a recess 44 of the disk 30 to limit the rotational movement of the disk to one revolution at each operation of the device and in such manner that the flat portion 31 at the completion of the revolution will be disposed 20 downwardly, as shown in Figure 2.
- The operation of the rotating device is as follows: With the parts of the device in the positions shown in Figures 1 and 2, the tone arm 19 as it swings inwardly toward the center 25 of the record imparts a corresponding movement to the arm 35, thus slowly feeding the trip member 34 inwardly toward the cam member 32. As the stylus 21 reaches the inner end of the sound groove, the trip member 30 34 engages the projection 33 as shown in Figure 3, and thus initiates a rotative movement of the cam member, and, the disk being fixed to the cam member, it is likewise rotated to cause the curved periphery thereof to move 35 into contact with the record 18. Under the rotative movement of the record, the disk is likewise rotated, thus continuing the rotative movement of the cam member and thus causing the latter to act upon the arm 35.
- 40 The shape of the cam member 32 is such that in the normal position thereof it is out of contact with the arm 35, as shown in Figure 3, but when rotated to the position shown in Figure 4 it engages and elevates the arm 35 sufficiently to elevate and thus move the stylus 21 out of contact with the record. Continued movement of the cam member through its frictional contact with the arm 35 reverses the movement of the arm, and as the arm is 45 attached to the tone arm 19, it will be clear that this reversal in movement will swing the tone arm outwardly to starting position. As the tone arm reaches starting position, the cam member 32 moves out of engagement with the arm 35, thus permitting the latter to be lowered and with it the tone arm, so that the stylus is now lowered into engagement with the record.
- The outward swinging movement of the tone arm is limited by the stop finger 40, it being understood that the stop arm 39 engages the stop finger, so as to check the outward movement of the tone arm at the proper instant. By making the stop finger adjustable and the trip member likewise adjust-

able, it will be manifest that the operation of the repeating device can be controlled to permit of its adaptation to different size records and to records having sound grooves of different lengths.

70

In the return of the disk 30 to the normal position shown in Figure 2, wherein its flat side 31 is disposed adjacent the record 18, the latch 43 engages within the notch 44 and thus functions to prevent further rotation of 75 the disk, so that the cam member 32 is likewise returned to normal position.

When changing records, the arm 24 can be elevated about its pivot 25 and latched in such position by the pin 26, whereby it will 80 not interfere with the application or removal of records to or from the turntable.

Although I have herein shown and described only one form of phonograph repeater embodying my invention, it is to be understood that various changes and modifications may be made therein without departing from the spirit of the invention and the spirit and scope of the appended claims.

I claim as my invention:

1. A phonograph repeater comprising an arm adapted to extend over a turntable, a disk rotatable on the arm and having a flat peripheral portion, a cam fixed to the disk for rotation therewith, a second arm secured to a tone arm for movement therewith, means operable by the second arm for initiating rotative movement of the cam to bring the curved periphery of the disk into contact with a record on the turntable whereby the disk and consequently the cam will be rotated with the cam frictionally engaging the arm to actuate the latter and thus return the tone arm to normal position, and means for controlling the rotative movement of the disk so that the flat portion thereof will be returned and held in disengaged position with respect to the record.

100

2. A phonograph repeater comprising an arm adapted to extend over a turntable, a disk rotatable on the arm and having a flat peripheral portion, a cam fixed to the disk for rotation therewith, a second arm secured to a tone arm for movement therewith, a projection on the cam, a tripping member on the second arm adapted to engage said projection, and co-operating stops on said arms.

110

3. A phonograph repeater as embodied in claim 2 wherein the tripping member and stop members are adjustable in the manner and for the purpose described.

120

4. A phonograph repeater as embodied in claim 2 wherein the second arm is movable to an elevated position, and means is provided for latching the arm in elevated position.

125

5. A phonograph repeater as embodied in claim 2, wherein the tripping member and one of the stop members are slidable on their respective arms to permit adjustment

130

thereof and mounted to maintain their adjustment when engaging the projection or other stop.

6. A phonograph repeater as embodied in claim 2 wherein a screw is carried by one of the stops to secure a finer adjustment thereof with respect to the other stop.

7. A phonograph repeater as embodied in

claim 2 wherein means is provided for adjusting the first arm vertically. 10

8. A phonograph repeater as embodied in claim 2 wherein the first arm is pivoted to occupy a horizontal position and an upwardly inclined position, and means for latching the arm in the inclined position.

HERMAN HOUSE.
